UNITED STATES PATENT OFFICE.

PAUL H. NEFFLEN AND JAMES F. GIFFEN, OF ELMINS, WEST VIRGINIA.

DOOR-LOCK.

963,632.

Specification of Letters Patent.

Patented July 5, 1910.

Application filed February 4, 1910. Serial No. 542,032.

To all whom it may concern:

Be it known that we, PAUL H. NEFFLEN and JAMES F. GIFFEN, citizens of the United States, residing at Elkins, in the county of 5 Randolph and State of West Virginia, have invented certain new and useful Improvements in Door-Locks, of which the following is a specification.

This invention relates to locks and latches, 10 and pertains especially to the class of cylinder locks, slidable tumbler.

The prime object of the invention is to provide a rack bar or locking bolt, slidable endwise through the lock so that it may be 15 lengthened or shortened as desired or as occasion may demand, and so that the said bar or bolt may be projected from either or both edges of the lock, and to provide means for sliding and locking the said bar or bolt.

20 A further object of the invention is to provide, in a cylinder door lock, novel and peculiar means for operating a locking bolt from either or both sides of the door.

A still further object of the invention is 25 to provide a tumbler slidably held by and between a pair of plate springs, a rack and pinion-operated locking bar or bolt, and means controlled by one of such springs for lifting the tumbler to permit the operation 30 of the said bolt.

A still further object of the invention is to provide special means for coupling and uncoupling the key-cylinders for operating the lock from either or both sides of the lock or 35 door to which it is applied.

Other objects, advantages and improved results will be found attainable in the practical application of the invention.

In the accompanying drawings forming 40 part of this application: Figure 1 is a perspective view of a lock embodying the invention and showing the locking bolt or bar in locked position. Fig. 2 is a side elevation with one side of the lock casing removed, 45 showing the slidable tumbler dropped. Fig. 3 is a similar view showing the slidable tumbler in lifted position. Fig. 4 is a sectional view on the line $x-x$, Fig. 3. Fig. 5 is a perspective view looking at the stem 50 end of the cylinder. Figs. 6, 7 and 8 are perspective views showing details of the invention. Fig. 9 is a perspective view of the slidable tumbler. Fig. 10 is an elevation 55 looking at the periphery of the spur wheel. Figs. 11 and 12 are detail views of the spur wheel connections.

The same reference numerals denote the same parts throughout the several views of the drawings.

Although the lock is specially intended for 60 bolting large and heavy doors, such as store or ware-house doors, it may be varied in size and shape for various other uses. And although ordinary tumbler cylinders and key plates, such as the well known "Yale" type 65 are shown, other cylinders and plates may be used, or we may devise special cylinders and plates, but for the purpose of illustrating and carrying out our invention, we have altered or modified said well known plates 70 and cylinders as will be hereinafter described.

The lock casing 1, may be of any desired shape or size, and of any of the well known types, but the one shown is adapted for 75 multiple keys, that is, a key for operating the lock from both sides thereof, and having a key plate 2 on each side thereof, in one of which plates a cylinder 3 is revolved, and the other of which plates has a similar cylinder 4, and each of said cylinders contain a tumbler 5 operated by a key 6. A locking bolt or bar 7 is provided with an inlaid or countersunk pinion rack 8 for a greater portion of its length, and this bolt or bar and 80 its rack may be varied in length according to the size of the lock, the bolt or bar being capable of projecting from either edge of the casing, so as to furnish a greater length of bar outside of the lock casing than 85 is possible in any lock of this character known to applicants. Owing to this extension feature of the bolt or bar, it is made solid throughout and without the usual cut-outs, cavities and reduction of any part 90 thereof in thickness, and therefore it is of the same width and thickness throughout. The rack 8 meshes with a pinion 9 loosely mounted on the inner end of the cylinder 3, 95 hereinafter more particularly referred to. The locking bar 7 has a stop lug or projection 10 on one side thereof central of its length, and travels through a slot 11 in a slidable tumbler 12 during the movement of the bar 7. From each end of the slot 11 100 extends a shoulder 13, which engages the lug 10 when the latter engages one side or the other of the lock casing, whereby the bolt 7 is locked or held against longitudinal movement, in either locked or unlocked position of the door to which the lock is applied. 110

The pinion 9 may be operated both from the inside or the outside of a door to effect the locking and unlocking thereof, or the lock may be operated only from the inside or from the outside as desired. In either or any event the pinion 9 is moved or revolved by turning one or the other of the key cylinders. When the lock is operated through the key cylinder 3, movement of this cylinder is imparted to the pinion 9 by the following described mechanism or its equivalent: the key is pushed inwardly against a follower 14, working in slots 15 of the cylinder 3 and controlled preferably by a spiral spring 16, attached to a disk 17, (or a coil spring may be used) having a yoke 18, through which, and the disk, a pair of stems 19 project from the inner end of the cylinder 3, and are provided with nuts 20 for securing the disk and its yoke to this end of the said cylinder with the spring in position to be compressed by the follower and permit the latter to be pushed between pins 21 on one side of the pinion 9, which is loosely mounted on this end of the cylinder so as to permit the cylinder to be turned therein until the projecting ends of the follower strike a pair of the pins 21, whereupon the pinion is turned with the cylinder. Said cylinder has pins 21^a opposite the pins 21.

The means for automatically sliding or lifting the tumbler 12, so that the pinion may slide the bar or bolt 7, comprises a collar 22 loosely mounted on the disk 17, and having a pair of lugs 23 projecting from the periphery thereof between the pins 21^a, and a pair of arms or cam pieces 24 projecting from the collar between and perpendicular to the lugs 23, and a stem socket 25 connected with the collar by said arms or pieces 24, a plate spring 26, having one end attached to the lock casing and the other end riding upon one of the arms 24, while the other of said arms holds the tumbler in raised or in lifted position so that the bolt lug 10 may travel through the tumbler slot 11, according to the direction in which the bolt is being slid by the rack and pinion, until the lug 10 reaches either end of the slot where it strikes the lock casing, by this time the pins 21^a, by engaging the lugs 23, will have turned the collar 22 and its arms 24 to allow the tumbler (under pressure of a spring 27) to drop or fall, leaving the lug 10 between the tumbler shoulder and the lock casing, in which position the bar is locked. It is obvious that a reverse movement of the parts by the key will unlock the bolt.

The key cylinder 4 is used to operate the rack and pinion from the opposite side of the lock to that of the cylinder 3, and said cylinder 4 has short projections or stems 28 upon each side of a slot 29. Instead of

the follower 14 a plate ring 30 has a bar 31, working in the slot 29 under a spring 32, which abuts against a disk 33 secured by the stems 28 on the inner end of the cylinder 4. The disk also holds a spur wheel 34 revolute on said cylinder end. The ring 30 is provided with a pair of pins 35, and when the ring is pushed by the key, the pins 35 mesh with the spur wheel so as to impart the movement of the cylinder to the spur wheel. The spur wheel has a hub or annular flange 36, in which the head 37 of a coupling stem 38 is loosely pivoted at 39. The stem 38 fits the socket 25 so as to turn the socket and its connections for operating the pinion.

It is obvious that various mechanical changes may be made in the several parts, and that means equivalent to such as shown and described may be employed for assembling and connecting the elements for transmitting the motion of the cylinders or either of them to the locking bar and its controlling tumbler.

Having thus described our invention what we claim as new and desire to secure by Letters Patent is:

1. In a lock of the class described, a locking bolt, a rack and pinion for operating the bolt, means for operating the pinion, a tumbler for locking and unlocking the bolt, and means operated by the pinion for sliding the tumbler across the bolt simultaneously with the bolt reaching its limit movement.

2. In a lock of the class described, a locking bolt having a lug on one face thereof, a rack and pinion for operating the bolt, a tumbler slidable across the bolt in engagement with the lug, means for operating the pinion from either side of the lock, and means operated by the pinion for sliding the tumbler.

3. In a lock of the class described, a locking bolt, a rack and pinion for operating the bolt, a tumbler slidable across the bolt, means for operating the pinion from either side of the lock, a key cylinder, means for coupling and uncoupling the pinion and cylinder, and means mounted on the cylinder and operated by the pinion for sliding the tumbler.

4. In a lock of the class described, a lock casing, a locking bolt having a rack therein so as to leave either end projectable from the lock, a stop lug on the face of the bolt and adapted to engage the ends of the lock casing for limiting the movement of the bolt, a tumbler having a slot through which the lug slides for making such engagement and means for operating the pinion.

5. In a lock of the class described, a locking bolt having a rack therein so as to leave either end projectable from the lock, a stop lug on the bolt and adapted to engage the

lock casing for limiting the movement of the bolt, a shouldered tumbler slidable across the bolt and having the said lug working through it and against the shoulders for locking the bolt, means for operating the pinion, and means operated by the pinion for sliding the tumbler.

6. In a lock of the class described, a locking bolt having a rack, a pinion for operating the bolt, a key cylinder on each side of

the lock for operating the pinion from either side thereof, and means connecting the cylinders with the pinion.

In witness whereof we hereunto set our hands in the presence of two witnesses.

PAUL H. NEFFLEN.

JAMES F. GIFFEN.
